(57) **CLAIM**

The ornamental design for a bottle, as shown and described.

DESCRIPTION

FIG. 1 is a front perspective view of a bottle showing my new design including a cap, spout, and base;

FIG. 2 is a front view of the bottle shown in FIG. 1;

FIG. 3 is a rear view of the bottle shown in FIG. 1;

FIG. 4 is a right side view of the bottle shown in FIG. 1;

FIG. 5 is left side view of the bottle shown in FIG. 1;

FIG. 6 is a top view of the bottle shown in FIG. 1;
FIG. 7 is a bottom view of the bottle shown in FIG. 1;
FIG. 8 is an exploded front perspective view of the bottle shown in FIG. 1;
FIG. 9 is an exploded front view of the bottle shown in FIG. 1;
FIG. 10 is an exploded rear view of the bottle shown in FIG. 1;
FIG. 11 is an exploded right side view of the bottle shown in FIG. 1;
FIG. 12 is an exploded left side view of the bottle shown in FIG. 1;
FIG. 13 is a top view of the bottle shown in FIG. 8;
FIG. 14 is a bottom view of the bottle shown in FIG. 8;
FIG. 15 is a further exploded front perspective view of the bottle shown in FIG. 1;

FIG. 16 is a further exploded front view of the bottle shown in FIG. 1;
FIG. 17 is a further exploded rear view of the bottle shown in FIG. 1;
FIG. 18 is a further exploded right side view of the bottle shown in FIG. 1;
FIG. 19 is a further exploded left side view of the bottle shown in FIG. 1;
FIG. 20 is a top view of the bottle shown in FIG. 15; and,
FIG. 21 is a bottom view of the bottle shown in FIG. 15.
The broken line showing of the pull tab, threads, cap threads, portions of the base of the bottle, the bottle base, the bottle cap, the central portion of the bottle, in relevant drawings shows unclaimed subject matter for the design in those drawings.
